(57) **CLAIM**

The ornamental design for a catheter tip, as shown and described.

DESCRIPTION

FIG. 1 is a perspective view of a catheter tip;
FIG. 2 is another perspective view thereof;
FIG. 3 is a left-hand side view thereof, wherein a right-hand side view is a mirror image of the left-hand side view;
FIG. 4 is a top view thereof, wherein a bottom view is a mirror image of the top view;
FIG. 5 is a front view thereof;
FIG. 6 is rear view thereof; and,
FIG. 7 is a view of the catheter tip in connection with a catheter splitter, wherein the catheter splitter is shown in broken lines and forms part of the environment.
The broken lines of FIGS. 6 and 7 do not form part of the claimed design.
The catheter tip is shown with a symbolic break in its length. The appearance of any portion of the article between the break lines forms no part of the claimed design.
